UNITED STATES PATENT OFFICE.

PETER BROADBOOKS AND LOUIS E. SMITH, OF BATAVIA, NEW YORK.

ARCH-SUPPORT FOR SHOES.

1,152,284.

Specification of Letters Patent. Patented Aug. 31, 1915.

Application filed August 22, 1914. Serial No. 858,023.

To all whom it may concern:

Be it known that we, PETER BROADBOOKS and LOUIS E. SMITH, citizens of the United States, residing at Batavia, in the county of Genesee and State of New York, have invented certain new and useful Improvements in Arch-Supports for Shoes; and we hereby declare that the following is a full, clear, and exact description thereof, reference being had to the accompanying drawings, which form part of this specification.

Our invention is a new and useful arch support for shoes, and the object is to provide the shoe with an arch prop which shall bear directly upon the surface upon which the shoe stands, so that the wearer of such shoe when standing will at all times have the arch or instep of his foot supported in a substantial manner.

Another object of our invention is to provide an arch supporting attachment for shoes which may be readily attached to shoes already in use and which will not mar the appearance of the shoes.

The support or prop may be made of metal, or rubber, or compositions, as may be desired, and is very simple and will uphold the weight and withstand the strain to which it is subjected in use.

The invention is capable of embodiment in various forms, some of which are shown in the accompanying drawings merely to illustrate the invention, and not as showing all the variations in form of which the invention is susceptible, which will be readily appreciated when the invention is understood.

We will explain the invention in detail with reference to the accompanying drawings, in which:

Figure 1 is a side view of a shoe showing one of the arch supports attached thereto. Fig. 2 is a plan view, and Fig. 3 is a sectional view of a simple support embodying the invention. Fig. 4 is a plan view, and Fig. 5 is a sectional view of another form of such support.

In the construction shown in Figs. 1, 6 and 7, the support embodies a metallic prop 1 depending from a top plate 2, which plate is provided with perforations 2^a for the passage of rivets or other devices by which it can be attached to the underside of the shank of the shoe intermediate the heel and ball portion thereof. This plate may be provided with a rearwardly extending lug 2^b which can be driven into the front and upper

part of the heel, as shown, to assist in attaching and positioning the support. The parts 1 and 2 may be cast integral, or united in any suitable way, as desired. The prop 1 is of such length that when the wearer of the shoe stands upon the ground this prop 1 rests upon the ground, or surface upon which the wearer is standing, and directly supports the arch thereupon intermediate the heel and ball of the shoe, as is obvious from Fig. 1.

As shown in Figs. 2 and 3, the support comprises a plate 3 adapted to be attached to the shoe shank and provided with openings 3^a for the passage of securing devices, and having lugs 3^b adapted to engage the heel; and to this plate is attached a central depending prop portion 4 which may be formed integral with the plate 3. This support is to be attached to the shoe shank in the location and with the same function and effect as the first described support.

In the form shown in Figs. 4 and 5, the support comprises a plate 5 provided with perforations 5^a by which it can be secured to the shank of the shoe, and having a central annular rib 5^b to which is attached the upper end of a prop 6 which may be of rubber or other suitable material. This support is also attached to the shoe and used in the same manner as the support first above described.

We have found by actual experience that the arch supports now in use do not give the desired results in holding up a broken instep; while our invention, providing a direct bearing prop under center of arch, will support the instep under any and all conditions, and being entirely outside the shoe may be readily attached to any shoe new or old. Broken arches are generally caused by unusual strain brought upon them in jumping, or by excessive weight bearing upon them. Our arch support will prevent the instep from breaking down. We provide resiliency or flexibility if desired by the use of rubber props.

A support placed either inside or outside along the curve of the arch of a shoe without a prop must necessarily have two bearing points, one bearing at each end of such support; our support has only one bearing point directly at the center of arch and will positively hold up a broken down arch, as plainly shown in Fig. 1. It is obvious that in each instance our arch support provides

a positive bearing directly under the center of the arch and will uphold the arch of the instep more surely than an inside support, and the most beneficial feature of our invention is the positive central direct prop supporting a flat arch or broken arch in the foot of the wearer.

It will be seen that each of the constructions described provides an arch support having a prop with a positive direct bearing on the surface upon which the shoe rests; and that the supports are very simple and inexpensive to manufacture, and can be easily applied to shoes; and the essential feature of the invention is a prop attached to the shoe and positioned underneath the shank and intermediate the heel and ball of the shoe.

What we claim is:

- 20 1. An arch support for shoes comprising a plate attached to the shank and a rubber block attached to said plate in front of and separated from the heel and forming a prop for the arch on the surface upon which the shoe stands.
- 25 2. An arch supporting plate for shoes having a cylindrical recess formed therein, and a circular block secured in said recess and serving as a prop bearing upon said

plate when pressure of the instep is brought 30 to bear upon it.

3. An arch supporting plate for shoes and boots having a ferrule integrally formed with said plate, and a circular block of non-metallic material secured within the ferrule.

4. An arch support for shoes, a ferrule formed with a flange secured to the lower surface of the instep of the shoe, and a block rigidly held within said ferrule forming 40 a prop bearing directly from the center of the shank of the shoe to the surface upon which the shoe stands.

5. An arch supporting plate for shoes comprising a thimble integrally formed with 45 said plate, and a circular block of rubber secured within the thimble and serving as a prop upholding the arch and adapted to contact the surface upon which the shoe rests.

In testimony that we claim the foregoing as our own, we affix our signatures in presence of two witnesses.

PETER BROADBOOKS.
LOUIS E. SMITH.
